N. K. TURNBULL

BATH FOR GALVANIZING

Filed Dec. 13, 1923

UNITED STATES PATENT OFFICE.

NICHOLAS KING TURNBULL, OF MILLPORT, SCOTLAND.

BATH FOR GALVANIZING.

Application filed December 13, 1923. Serial No. 680,559.

To all whom it may concern:

Be it known that I, NICHOLAS KING TURNBULL, a British subject, residing at Millport, county of Bute, Scotland, have invented certain new and useful Improvements in Baths for Galvanizing, of which the following is a specification.

This invention relates to baths for galvanizing metal articles such as wire, wire netting, sheets, tubes and other products by immersion in molten zinc in which the zinc or spelter floats upon a layer of heavier metal such as lead to which the heat is applied.

It has been customary to heat galvanizing baths externally and the invention is designed to heat the bath internally without the escape of the products of combustion into the atmosphere and to successfully apply gas or oil firing to the bath.

According to the invention the galvanizing bath is constructed of steel with a series of tubes, fitted with gas or oil burners, welded therein near the bottom and submerged in the molten lead.

The invention will be described with reference to the accompanying drawings.

Fig. 1 is a longitudinal section through galvanizing bath.

Fig. 2 is a transverse section of same.

Fig. 3 is a longitudinal section through modified form of bath.

The galvanizing bath A is made of steel of ordinary form and at or near the bottom is fitted with heating tubes B either longitudinally or transversely of the bath which are welded into the sides of the bath. At

the end of each tube a gas or oil burner C is fitted, each burner being separately controlled by a valve D supplied with fuel from a pipe E. The opposite ends of the tubes B connect with a flue or duct B' by which the products of combustion are carried away to the chimney.

The tubes B are submerged in molten lead F to a depth of two or three inches. Above the surface of this molten lead collects the dross G that accumulates from the articles being galvanized whilst above this again is the molten zinc or spelter H.

The bath A is formed with an inner lining A' of refractory material closely secured to the sides and ends of the bath but not to the bottom so that the bath may expand equally with the tubes, and which is preferably a non-conductor of heat and on

which molten zinc has little or no action, and the outside of the bath A is preferably lagged with a heat insulating material A² such as slag wool before being built up with bricks A³.

By this construction the baths are made more comfortable for the operatives to work near particularly during hot weather and no obnoxious fumes escape into the work shop as occurs with coke fired baths and also the baths are more accessible to the operatives than are any externally fired baths.

In the construction shown in Fig. 3 the tubes B are fitted with burners and fired from both ends, the flue or duct B' being arranged to take away the products of combustion or the firing may take place at B², the products of combustion passing along the tubes to chimney ducts at both ends of the bath.

The products of combustion after doing their work in the bath can be utilized to raise steam, dry articles, melt additions of zinc for the bath or for any other works purposes, or for preheating the air or gas for combustion. The galvanizing baths may be of any size or dimensions as the heating of the baths is under immediate and simple control and as the baths rest on a solid base

having no flues underneath or on their sides they can be insulated on the outside with a non-conducting material which, together with the internal lining A' of a material unacted on by molten zinc and a non-conductor of heat, ensures a minimum loss of heat by radiation.

The heating tubes can be so arranged in relation to the work being galvanized and the heat in them so controlled as to ensure if so desired a practically uniform temperature throughout the bath. In the old type of baths heated from the sides and doing continuous work such as wires the zinc at the sides was always slightly hotter than at the centre.

Gas for use in these baths should be thoroughly clean and dry, this with the high velocity of the products of combustion in the tubes ensures them remaining indefinitely clean but easy access is arranged so that they may be scoured with a wire brush every six months or as required. It is considered that galvanizing baths constructed as described present the following advantages over the older type (a) the output can in

most cases be considerably increased in some processes very materially (b) the baths last indefinitely (c) the work at the baths is easier, cleaner and cooler (d) the product is 5 more uniform (e) the fuel costs including handling of fuel and ashes are low (f) the bath can be made lighter than in present practice (g) there are no reasonable limits to the dimensions of a bath either in width or 10 length as heat can be applied to ensure a uniform temperature at every part of it.

What I claim as my invention and desire to protect by Letters Patent is:—

An iron or steel bath for galvanizing metal 15 articles in which the zinc or spelter covers a layer of heavier metal such as lead comprising in its construction a tank to contain the metal, a plurality of steel heating tubes se-

cured into the ends of the tank and passing through the tank near the bottom in such 20 position as to be submerged in the heavier metal, a plurality of burners fitted to heat the tubes, a flue to carry off the products of combustion from the tubes, an insulating lagging around the exterior of the tank and 25 an inner lining of refractory material closely secured to the sides and ends of the tank and extending below the surface of the lead.

In testimony whereof I have hereunto set my hand in presence of two subscribing witnesses.

NICHOLAS KING TURNBULL.
